US00D790364S

(12) **United States Design Patent** (10) **Patent No.:** **US D790,364 S**
(45) **Date of Patent:** **** Jun. 27, 2017**

(54) **CONTAINER**

(71) Applicant: **Rockline Industries, Inc.**, Sheboygan, WI (US)

(72) Inventor: **Donald C. Neitzel**, Petersburg, MI (US)

(73) Assignee: **Rockline Industries, Inc.**, Sheboygan, WI (US)

(**) Term: **14 Years**

(21) Appl. No.: **29/499,834**

(22) Filed: **Aug. 19, 2014**

(51) **LOC (10) Cl.** **09-01**

(52) **U.S. Cl.**

USPC **D9/734**

(58) **Field of Classification Search**

USPC D9/414, 424, 430, 431, 499, 730, 734; D3/201, 304, 315; D6/515, 518, 519, D6/521, 522, 523; 206/205, 210, 216, 206/233, 389, 395, 494, 581, 812; 221/33, 36, 45, 46, 47, 48, 52, 199, 255, 221/259, 305, 309; D7/601, 602, 631

(57) **CLAIM**

The ornamental design for a container, as shown and described.

DESCRIPTION

FIG. 1 is a perspective view of a container according to the claimed design;

FIG. 2 is a front view thereof;

FIG. 3 is a right side view thereof, the left side view being a mirror image thereof;

FIG. 4 is a rear view thereof;

FIG. 5 is a top view thereof;

FIG. 6 is a bottom view thereof; and,

FIG. 7 is a bottom perspective view thereof.

The broken lines shown represent unclaimed subject matter and form no part of the claimed design.

1 Claim, 7 Drawing Sheets
